(57) **CLAIM**

The ornamental design for a party hat having inflatable balloon, as shown and described.

DESCRIPTION

FIG. 1 presents a front view of a new design for a party hat having inflatable balloon that shows the balloon as partially inflated, in use.

FIG. 2 presents a side view of the party hat that shows the integral inflation tube extending beyond the hat; and, FIG. 3 presents a rear view of the party hat that shows the integral inflation tube, extending beyond the hat.

In the drawings the broken line showing of the human head is for illustrative purposes only and forms no part of the claimed design.
